CAR TOP LUGGAGE CARRIER

William L. Brown, Garden City, and Jackie E. Fitzgerald,
Wayne, Mich., assignors to Fabricon Products, River
Rouge, Mich., a corporation of Ohio

Filed Feb. 27, 1961, Ser. No. 64,059

Term of patent 14 years

(Cl. D14—27)

FIG. 1

FIG. 2

FIG. 1 is a perspective view of the car top luggage carrier embodying our novel design.

FIG. 2 is a side elevation thereof.

FIG. 3 is a front elevation thereof.

FIG. 4 is a rear elevation thereof.

The dominant features of our design reside in the portions shown in full lines. The side not shown is a mirror image of the side shown.

We claim:

The ornamental design for a car top luggage carrier, as shown and described.
